UNITED STATES PATENT OFFICE.

RICHARD REGIS GORDON-BARRETT, OF AYLESBURY, ENGLAND.

APPARATUS FOR SUPPLYING MOISTENED AIR TO INTERNAL-COMBUSTION ENGINES.

Application filed August 19, 1925, Serial No. 51,272, and in Great Britain April 29, 1924.

This invention has for its object the provision of an improved apparatus or device for supplying moistened air to the mixture passing through the induction pipe of an internal combustion engine.

To that end the invention contemplates a novel construction and arrangement of parts which may be easily manufactured and assembled and then installed as a unit in the fuel supply system of an internal combustion engine.

These and other objects will more fully appear and the nature of the invention will be more clearly understood from the detail description in the following specification, the subject matter of the claims, and the several views in the accompanying drawings, in which:

In order that the invention may be the more readily understood, reference is to be had to the following description and accompanying sheets of drawings, wherein:

Figure 1 is a longitudinal sectional view illustrative of a practical embodiment of the invention.

Figure 2 is a view, partly in elevation and partly in section, illustrative of a detail hereinafter referred to.

Figure 3 is a vertical sectional view illustrative of a modified embodiment of the invention.

Figure 4 is a longitudinal elevational view illustrative of the application of the control valve of the apparatus or device.

Figure 5 is a plan view of said control valve.

Figure 6 is an elevational view of said control valve shown separately.

Figure 7 is a sectional plan view taken on line x, x of said Figure 6.

Figure 8 is a sectional plan view taken on line y, y of said Figure 6.

In the preferred embodiment of the invention, the same includes in its organization an inlet section which interfits with a combined filtering and guiding section 3, the latter in turn being connected with an air intake section 6 having a cylindrical cup-like member 7 telescopically fitting into a main body section 16 which is provided with suitable means for connecting it in the fuel intake line. The first part or inlet section 1 is provided with a centrally disposed and bored nipple 2 for pipe connection with a water tank, not shown in the drawings.

Between the first part 1 and the second part or filtering or guiding section 3, which parts 1 and 3 screw one into the other, there is provided a fine wire gauze or strainer 4 to prevent grit or other foreign matter contained in the water from entering the centrally disposed fine jet orifice 5 which is formed in said second part 3.

To this second part 3 there is screwed one end of the third part 6 of the casing, said third part 6 at its other end being hollowed out to form a cylinder 7 which communicates by way of a longitudinal and central bore 8 with the jet orifice 5 aforesaid, and through the wall of said part 6 there is provided one or more small air ports 9 which communicate with the longitudinal bore 8 aforesaid.

The admission of air may be regulated by a grub screw operated by a screw-driver, or, as shown in said Figures 1 and 2, by means of a screw 10 provided with a large milled head 11 for operation by hand.

In the cylinder 7 of the third part or air intake section 6 there is provided a piston 12, said piston 12, which is a loose fit in said cylinder 7, being provided with three peripheral shallow grooves 13, and also carrying a long thin needle or wire 14 which extends through the longitudinal bore 8 of said third part 6 into the jet orifice 5, said needle or wire 14 being at all times in said jet orifice and serving to break up the water sucked through said jet orifice. Around the periphery of the piston 12 a series of minute holes 15 are drilled for a purpose to be described.

On the third part 6 there screws the fourth part or main body section 16 which envelops the cylinder or cup 7 and forms an expansion and mixing chamber 17. A small channel or duct 18, which terminates in a fine jet orifice 18^a, is drilled in the part 6, connects the chamber 17 with the conical chamber 19 formed in the female portion of the part 6 aforesaid. This duct and orifice form an auxiliary atomizing passage for supplying water to the mixing chamber.

The part 16 is provided with a longitudinal and centrally bored nipple 20 for a valve-controlled pipe connection to the induction pipe of the engine, and between the inner end of the piston 12 and the end wall of a recess 20^a, which communicates with the bore 22 of the nipple 20, there is interposed

a light spring 21 which normally holds the outer end of said piston 12 flush with the end of the cylinder 7.

The fourth part 16 may, as shown in Figure 2, be provided with a simple means of external regulation of the spring 21, such means consisting of a ferrule 23 screwing into the part 16 and also into a union 24 to which the valve-controlled pipe connection 10 to the induction pipe is connected, adjustment being effected by screwing in or out the ferrule 23, locking, after adjustment, being by means of the nuts 25.

The action of the above described apparatus or device is as follows:—

Depression in the induction pipe causes the piston 12, against the action of the spring 21, to travel along in its cylinder 7, thus agitating the needle 14 in the jet orifice 5 and facilitating the admission of small quantities of water filtered or strained through the gauze 4 and causing it to flow into the conical water collecting chamber 19 and through the longitudinal bore 8 of part 6 of the casing into the cylinder 7; at the same time air is also induced through the adjustable port or ports 9 aforesaid into said bore 8 to mix with the water. The air and water are then drawn past the loosely fitting piston 12, with the result that as said air and water pass and contact against the grooves 13 of the piston 12, said air and water are commingled and then spread out in the chamber 17 where the now moistened air also meets and mingles with the small quantities of water sucked in through the duct 18 and orifice 18^a from the conical water collecting chamber 19, the moistened air then passing by way of the bore 22 to the induction pipe where it meets the incoming charge of fuel.

When the depression in the induction pipe is at its highest point, i. e. when the throttle is nearly closed or the pilot jet only of the petrol carburetter is in use, the piston 12 is drawn against a machined seating 26 at the end of the expansion and mixing chamber 17 in part 16 of the casing, and no vapour or air can pass to the induction pipe not shown save by the small holes 15 around the periphery of this end of the piston 12.

Referring now to the modified arrangement of apparatus or device shown in Figure 3 of the drawings, this apparatus or device consists of a three-part casing of cylindrical shape which, when used in conjunction with internal combustion engines for motor cars, is fixed in a vertical position on the dashboard or other convenient place in the car. The first or lower part 1^a of the casing is fitted with a centrally disposed and bored nipple 2^a for pipe connection with a water tank located in any convenient position, and at any level. The upper end of part 1^a is closed by a seating 27 provided

with a centrally disposed jet orifice 5^a therein, whilst in the lower part of 1^a two fine gauze filters or strainers 4 are fitted.

On the upper end of part 1^a which part is exteriorly threaded, is screwed the lower end 70 of the second part 6^a, of the casing, a nut 28 on the threaded portion of part 1 being fitted for locking said parts 1 and 6^a together when in required adjusted position.

In the upper end of part 6^a there screws 75 the lower end of the third part 16 of the casing, which part 16^a at its lower end is provided with a seating 29 to receive the head of a mushroom valve 30 which is positioned centrally within the part 6^a aforesaid, the underside of said valve 30 carrying a vertically depending long fine needle or wire 14^a which passes through a hollow inverted cone 31 which by its apex is adapted to make a close seating on the valve seat 27 85 of the part 1^a of the casing, this needle or wire 14^a extending into the jet orifice 5^a in said seating 27. Further, a nut 31^a on the screwed portion of the part 16^a is fitted for locking together said parts 6^a and 16^a when 90 in required adjusted position; and, further, said part 6^a of the casing is provided with ports 9^a for the admission of air, said ports 9 being fitted or not with means for adjustment of the passage therethrough of air. 95 The cone 31 is a close fit on the needle or wire 14^a.

The nut 28 serves to lock the parts 1^a and 6^a together, after the insertion of the cone 31 and the mushroom valve 30, whilst the nut 100 31^a serves to lock the parts 6 and 16 together after regulating the distance between the mushroom valve 30 and its seating 29 in the lower end of part 16^a, which part 16^a is at its upper end provided with a centrally disposed bored nipple 20^a for a valve-controlled pipe connection to induction pipe of engine. 105

The mixing of water and air takes place in the parts 6^a and 16^a of the casing, water being sucked in through the strainers 4^a and jet orifice 5^a in said part 1 and split up through its contact with the wall of the cone 31 in said part 6^a and further pulverized by the rush of air sucked in through ports 9^a in said part 6^a, the quantities delivered being regulated by screwing in or out the parts 1^a, 6^a and 16^a of the casing, whilst the quantity of air may be controlled by suitable means not shown. 110 115

The action of the above described modification of the apparatus or device is entirely automatic in action, controlled by the suction of the engine, i. e. through the depression which occurs in the induction pipe. When the throttle is closed or nearly closed (on deceleration or when starting up) the mushroom valve is drawn up against its seating, thus preventing the admission of water vapour (water and air mixture). 125

From the foregoing description and an 130

inspection of Figure 3 of the drawings, it will be readily understood that no springs enter into the construction of the modified arrangement of apparatus or device; thus there is absolutely nothing to get out of order, or need for replacement.

The control valve or tap may be connected directly to the nipple of the part 16^a of the first described apparatus or device, or 10 it may be connected by a flexible pipe to the nipple of part 16^a of either of the described apparatus or device and by another flexible pipe to the induction pipe, said control valve or tap in these latter cases being located on 15 the dashboard or other convenient part of the car.

In Figure 4, the control valve or tap, which is shown connected by pipe connection 32 to the fourth part 16 of the device or 20 apparatus first described, is provided with a pipe for connection with the induction pipe. The valve or tap consists, as shown in Figures 5 to 8, of a cylindrical body 34 with a flanged head 35 thereto marked 25 "Off", "Vap", "Air", said member 34 being longitudinally and centrally bored to receive a plug 36 fitted with operating knob 37 with pointer thereon, said plug towards its lower end being provided with a horizontal bore 38 extending therethrough and a horizontal bore 39 extending from said bore 38 to the peripheral wall of the plug 36, which plug at its upper end is provided 30 with a recess 40 for the engagement therein of a spring-pressed ball 41 to hold said plug 36 in its midway position, indicated by "Vap" on the head 35, and in this position the bore 38 of the plug 36 aligns with the 35 ports 42 and 43 in the body of the valve or tap 34, said ports 42 and 43 communicating respectively with pipe connection 32 to the moistener or mixer, and by pipe connection 33 with induction pipe of engine so that there is free passage for the admission of 40 water vapour (water and air mixture) to

induction. But on turning operating knob 37 to position "Air" on Figure 5, bore 39 and bore 38 register with ports 43 and 44 in the body of the valve or tap 34, allowing of the admission of extra air to induction 50 pipe to act as a brake means and also as a cooling means on turning plug to position "Off", then ports 42 and 44 are in communication, but nothing takes place as there is no suction on the moistener or mixer. 55

It will thus be seen that one of the main objects of the invention is to provide apparatus or devices as above set forth which are fool-proof and cannot get out of adjustment; are automatic in action and supply 60 just the required amount of atomized water at all or any engine speed; ensuring complete combustion and the absence of any residue which in the ordinary way produces carbon deposits, pitted valves and other undesirable results. 65

I claim:—

A fuel moistening device for internal combustion engines comprising a main body section providing a vaporizing chamber having an outlet passage, an air intake section fitted to the body section and including a cup-like member projecting into the said chamber, a water collecting chamber said air intake section also having a passage communicating with said water collecting chamber, through one wall thereof a section filtering means fitted into the air intake section and having a central bore and a recess and forming another wall of said water collecting chamber, and a hollow valve having perforations therein and operating in said cup-like member, said valve also having a stem extending through the air passage of said intake section, and a spring for normally 70 maintaining said valve away from the outlet passage of the main body section. 75

In testimony whereof I have affixed my signature hereto this 30th day of July 1925.

RICHARD REGIS GORDON-BARRETT.
